UNITED STATES PATENT OFFICE.

LE DRU R. POMEROY, OF SYRACUSE, NEW YORK.

ADJUSTABLE WINDOW-SCREEN.

SPECIFICATION forming part of Letters Patent No. 444,409, dated January 6, 1891.

Application filed April 25, 1889. Serial No. 308,577. (No model.)

To all whom it may concern:

Be it known that I, LE DRU R. POMEROY, a citizen of the United States, residing at Syracuse, in the county of Onondaga and State of New York, have invented certain new and useful Improvements in Adjustable Window-Screens; and I do hereby declare the following to be a full, clear, and exact description of the invention, such as will enable others skilled in the art to which it appertains to make and use the same, reference being had to the accompanying drawings, in which—

Figure 1 is a rear elevation of my improved window-screen in its entirety—*i. e.*, that face or side of the screen that usually faces or stands toward the exterior of the window opening on the street—with portions represented as broken away for clearer illustration of certain details of construction. Fig. 2 is an enlarged isometric detail of an upper corner of my window-screen with guide-strips removed; Fig. 3, an enlarged horizontal transverse section taken on line xx , Fig. 2; Fig. 4, an enlarged vertical transverse section taken on line yy , Fig. 1; Fig. 5, an enlarged isometric detail illustrating a slight modification in the contour of the flange of the top rail of the screen-frame in cross-section; Fig. 6, an enlarged isometric sectional detail illustrating another slight modification of above-named parts; Fig. 7, an enlarged isometric sectional detail illustrating a flanged portion at either side of the upper part of the top rail of the screen-frame, and Fig. 8 a longitudinal side elevation of one of the metallic side rails of the screen-frame while bowed and prior to its insertion in the top and bottom rails of the screen-frame.

Similar letters and figures of reference indicate corresponding parts throughout the several views.

My invention relates to that class or kind of window-screens termed "adjustable," and so constructed as to permit of their lateral adjustment within a window, (or window-frame,) whereby they are adapted to correctly fit windows of varying width.

The object of my invention is to provide an improved window-screen of the class described that is so constructed as to prevent the ingress of flies and other winged insects into the room at or about the upper portion

of the horizontal sliding top rail of the window-screen or wings whereon the upper window-sash rests perpendicularly or abuts against transversely at its back face without regard to what length or width the complete window-screen is horizontally contracted or extended in line with the window-opening; that is readily and positively adjustable laterally to varied-width windows; that is easily accessible and admitting of expeditious manipulation of its movable parts; that may quickly be secured in desired position; that, while possessing the requisite degree of durability and strength, has desired lightness in weight and correspondingly pleasing and attractive to the eye; that is expeditious and simple of manufacture and constructed at comparatively small expense.

My invention consists, essentially, in the several novel features of construction, operation, and adaptation hereinafter described, and which are specifically enumerated in the several clauses of claims hereto annexed.

It is constructed as follows: A is a rectangular screen-frame provided with suitable screen fabric a , and consisting of the parallel horizontal top and bottom rails $b c$, respectively, and the metallic side rails $d d$, formed respectively of an elongated strip of sheet metal bent over upon itself parallel with its length sufficiently apart to leave a slight space between its adjacent overlapping portions, and which, prior to the securing taut of the screen fabric, is slightly bowed longitudinally, the central horizontal projection of the bow being at its curved edge.

My manner of procedure in the utilization of the previously-bowed metallic side rails $d d$ in conjointly constructing the screen-frame A and making taut the attached screen fabric is substantially as follows: I take the top and bottom rails $b c$ and insert wire-cloth or other suitable screen fabric therein, securing the same by nailing or other means, as is usually employed. I next take the bowed metallic strips or rails $d d$ and insert the ends of the same in the ends of the top and bottom rails $b c$, at the same time inserting the perpendicular edges of the screen fabric loosely in the slots $g g$ of the metallic strips $d d$ and then secure the said metallic strips to the top and bottom rails with pins or bolts, as at

e. I next press inward upon the bowed metallic side strips until they are straight, or practically so, longitudinally. I then press the encompassing sides of the metallic strips 5 *d d* tightly upon the inclosed screen fabric, and then I release the inward pressure hereinbefore described, which release of pressure creates a tension laterally upon the screen fabric, causing it to lie taut, smooth, and uniform.

In practice I find that sometimes it is not essential to have the metallic side rail previously bowed longitudinally, as sufficient smoothness and evenness of the screen fabric 15 may be attained by utilizing at the outset a side rail which is perfectly straight and devoid of longitudinal curvature. At the interior or central edge of the top and bottom rails *b c*, respectively, are the ordinary slight 20 longitudinal grooves or slits in which is inserted the upper and lower edges of the screen fabric in the usual or any preferred manner.

It is obvious that my employment of suitably-bent sheet metal for the side rails of the 25 screen-frame produces a much lighter rail than the customary ones constructed of wood and grooved, besides costing less to manufacture.

The horizontal top rail *b* of the screen-frame terminates at its rear upper portion with a 30 flange (or flanges) *1*, that continues longitudinally therewith from end to end of said rail, which flange is preferably an integral part of the entire rail.

The letter *B* designates parallel vertical 35 wings, U-shaped in cross-section, adapted to slide vertically upon the guide-strips *h*, vertically secured at the sides of a window, their edge tongue portion *i* engaging the grooves *k* of the guide-strips.

40 *l* is a narrow longitudinal slot cut into the inner edge of the respective wings *B B*, (sufficiently wide transversely to permit the easy passage of the metallic side rails,) and extending into them about two-thirds (or thereabout) their width from edge to edge, thus forming a slot whose depth on a horizontal plane is about double the width of the metallic side rail that it encompasses, and over which it horizontally slides in a forward or 45 rearward direction.

At the top portion of the respective wings *B B*, I cut a transverse horizontal channel or slot *m*, open at either end and in line longitudinally with the flanged top rail *b*. This 55 slot being wider than the vertical slot *l* in the wing, it forms at the point of connection therewith and to the outer edge the shoudered portion *n*, the whole forming a seat adapted to support and guide the contacting 60 portions of the flanged top rail *b*, when the adjustable wing *B* is at rest or being moved inward or outward in line horizontally with the direction of the screen-frame.

The slot *m* is of sufficient depth to allow the 65 top horizontal face of the upper rail *b* to lie evenly with the top surface of the front wall *o* of the slot of the wing *B*, as shown. As

illustrated at *p*, the rear wall *o'* of said slot terminates a short distance below the level of the adjacent wall, and to such degree as 70 to allow the bottom portion of the flange *1* of the top rail *b* to move along its top edge and the top surface of said rail to lie evenly with the top surface of the front wall *o* of the slot, (or front of the window-screen,) the flanged 75 portion *1* of the rail projecting outward in line with the rear vertical face of the wing or wings. The top horizontal edge of the rear wall *o'* forms an auxiliary seat *r* for the flanged rail *b*, the flange *1* thereof lying upon 80 it, as shown.

At a suitable distance from the upper and lower extremities of the respective wings *B B*, I cut out a sufficient portion of the wood upon that side of the longitudinal vertical 85 slot *l* to permit of the free insertion and pivoting therein of a metallic toothed cam *2*, of such contour and so mounted that when in its normal position it securely holds or retains the screen-frame *A* and adjustable wings *B B* in positive unyielding contact with each other, preventing any lateral movement of the said frame or wings. This effect is assured by the employment of a small spring *s*, secured within the recess in which the cam is mounted and bearing against the cam-arm *t*, whereby the teeth or frictional surface of the cam-body is held normally in close contact with the inner horizontal edge of the top or bottom rail *b c* of the screen-frame, as 90 clearly illustrated in Figs. 1 and 4 of the drawings.

When it is desired to adjust the complete window-screen to a certain-width window, and consequently move laterally the wings *B B*, that encompass the side rails *d d*, I press 105 inwardly upon the cam-arms, thus throwing the cam-teeth out of contact with the inner horizontal edge of the top or bottom rail *b c*, thereby permitting (during the continuance 110 of the inward pressure upon the cams' arms) the sliding inward or outward laterally of one or both the wings to desired position.

3 represents a vertical slit cut centrally into the exterior edge of the respective wings 115 for the purpose of giving flexibility to the walls at either side of the slot *m*, and particularly of the vertical slot *l*, permitting the springing apart transversely of the aforesaid parts without danger or liability of the wing 120 splitting longitudinally, particularly at its solid external vertical edge, when subjected to the transverse outward pressure or strain superinduced by the passage of the top or bottom rail *b c* along the slot *m* of the wing. 125 Ordinarily devoid of this slit *3*, the free extremities of the walls of the wing, owing to its structural weakening incident to the taking away of material in the formation of the longitudinal vertical groove *l*, incline transversely more or less toward each other, which, 130 retarding to some degree the free passage of the interposed top or bottom rail of the screen-frame through the slot *m* or slot *l*, subjects

the wing B to liability of longitudinally splitting at its external or outer vertical edge, as without the slit 3 the central outward pressure against the encompassing contracted extremities must result in the straining or rupture of the weakest portion, the solid edge wall of the wing.

It will be readily observed and understood that by the formation of the slit 3 into the external vertical edge of the wing B a space is created that allows for the springing apart of the free ends of the wall portions thereof without liability of splitting the external edge portion of the wing, from the fact that the springing apart of the aforesigned extremities simply brings the material at either side of the slit 3 into contact yieldingly, and thus in effect making the integral wing elastic or springy at the very point where it is absolutely required.

My prime and all-important object (as may be observed) in constructing the horizontal top rail *b* with a side flange 1, whose top surface lies flush with the top surface of the front wall or face *o* of the respective wings, and having the top of the rear wall or face *o'* of the respective wings terminating at a point below the top edge of the adjacent front wall equal to the perpendicular thickness of the flange 1 of the top rail *b*, is that when the lower transverse rail of the upper window-sash lies upon the top edge of the flanged top rail, or, on the other hand, abuts at a side against the rear or flanged side of the window-screen, there will be neither any vertical nor horizontal transverse opening or space left between the lower rail of the upper window-sash and the flanged top rail of the window-screen, irrespective of the degree said screen may be extended or contracted laterally to fit a window, thus absolutely preventing the ingress at the point of contact of the window-screen with the upper window-sash of flies or other winged or wingless insects into the room.

Although preferably I construct my top rail *b* with a flange 1 upon but one side thereof and rectangular in cross-section, I do not limit nor confine myself to that specific arrangement or contour, as it is obvious that when deemed preferable or desirable the top rail *b* of the screen-frame may be flanged at both sides, and the flange may be of preferred or varied shape or contour in cross-section (as exemplified to some degree in the modifications shown in the drawings) without a departure from the spirit or scope of my invention; also, that in connection with my flanged top rail the respective walls of the wing B may be of either corresponding or different height, according to the specific form in cross-section of the flange or flanges of the top rail, and embody my invention.

Having thus fully described my invention, what I claim as new, and desire to secure by Letters Patent, is—

1. In a window-screen, a screen-frame comprising top, bottom, and side rails secured together, the horizontal top rail thereof having upon one or both its sides flush with its top surface a lateral flange extending longitudinally therewith, vertical wings U-shaped in cross-section embracing the lateral edges of the screen-frame by means of a respective lateral slot, and the flange or flanges of the top rail, whose upper horizontal surface lies flush with the upper horizontal surface of the body of said top rail, adapted to rest at their end portions upon the top edge or edges of the transversely U-shaped wings, combined and operating together substantially as described.

2. The combination, in a window-screen, of a rectangular screen-frame comprising top, bottom, and side rails, its horizontal top rail having at its upper portion and flush with its top surface a lateral flange extending longitudinally therewith, vertical movable wings of U shape in cross-section disposed, respectively, at opposite extremities of the screen-frame, the top rail of the screen-frame whose lateral flanged portion projects outwardly substantially in line with the vertical face of the wings extending beyond the side rails of the screen-frame and fitting at each protruding end in a horizontal slot formed in the top portion of the respective wings, said wings inclosing by their vertically-slotted portions the side rails of the screen-frame and adapted to longitudinal adjustment thereon, all the said parts being constructed and operating together substantially as described, and for the purposes specified.

3. In a window-screen, a rectangular screen-frame comprising top, bottom, and side rails secured together, the horizontal top rail thereof having upon one or both its sides flush with its top surface a lateral flange extending longitudinally therewith, vertical wings U-shaped in cross-section respectively embracing the lateral edges of the screen-frame by a lateral slot, a horizontal slot at the top of said wings adapted to receive a projecting end of the flanged top rail of the frame, and cams mounted at the upper and lower portions of the interior of the U-shaped wings, that are adapted to be thrown into or out of frictional contact or engagement with the adjacent top or bottom rails of the screen-frame and hold it and the encompassing wings against lateral movement or displacement, combined together substantially as described, and for the purposes herein specified.

In testimony whereof I affix my signature, in presence of two witnesses, this 3d day of April, 1889.

LE DRU R. POMEROY.
